UNITED STATES PATENT OFFICE.

THURE A. QUART, OF HARTFORD, CONNECTICUT.

OIL-BURNING APPARATUS.

Application filed August 26, 1927. Serial No. 215,694.

This invention relates to oil burning apparatus and particularly to apparatus of this character which is especially adapted for use with house heating furnaces. Such devices are ordinarily operated by persons of inexperience in mechanical principles who are prone to neglect mechanism requiring frequent attention and to open too far or not far enough hand operated valves such as enter into the make-up of many heating systems now on the market. Primarily the object of my invention is the provision of apparatus entirely free of valves and other parts needing frequent manual adjustment,— an apparatus so designed that when once installed the turning of a switch will accomplish every requisite.

In the accompanying drawings I have shown one convenient form of embodiment of my invention which to enable those skilled in the art to practice the same will be set forth fully in the following detailed description while the novelty of the invention is defined in the appended claims.

25 In the drawings,—

Figure 1, is a plan view of apparatus embodying my invention. Figure 2, is a side view of the apparatus shown in Fig. 1. Figure 3, is a side view of important details of my invention with certain parts shown in section or partly in section. Figure 4, is a transverse sectional view on line 4—4 of Fig. 3. Figure 5, is a sectional view on line 5—5 of Fig. 4. Figure 6, is a sectional view of the fire pot on line 6—6 of Fig. 1.

Referring to the drawings several of the essential elements of the oil burning apparatus illustrated may be briefly described as follows. The fire pot, designated by 1, is of a type adapted to be set up on its standard 2, within such furnaces as are commonly used for heating residences or other buildings. Connecting the fire pot with a blower 3, is an air conduit 4, through which air under pressure is forced to the fire pot when the blower is operated as by the electric motor 5. Both the blower and motor may as shown be mounted on a bracket 6, supported in a standard 7, so as to permit in some suitable and convenient manner of vertical adjustment of the bracket for a purpose that will herein-after more fully appear.

Within the fire pot 1, is a casting 8, comprising a burner wherein oil is vaporized and ignited as long as it is properly fed thereto by the feed devices which will presently be

described. Initial vaporization and ignition of the oil is effected by a pilot flame of gas delivered against the side of the burner through a jet 9, to which gas is supplied by the pipe 10, see Figs. 1 and 6. The air current delivered through the burner assumes a circular motion in the fire pot and in order that this may not extinguish the pilot flame a baffle 11, is depended from the burner at the side thereof. A small opening 12, however is formed in the baffle to permit sufficient vaporized oil to pass therethrough to become ignited by the pilot flame.

Means for controlling the supply of oil delivered to the burner include several devices introduced into the pipe line 13, leading from the main supply reservoir. The first of these devices is an automatic safety shut-off valve 14, and next to this is an oil feed controlling device 15, which comprises a chamber 16, containing a float 17, adapted to open and close a valve 18, according to requirements to maintain a constant level of oil as designated by line X—X, Fig. 3. Should this valve fail to function in shutting off the oil, an overflow pipe 19, is provided to conduct the excess oil to the pan 20, which when weighted with a predetermined amount of liquid, actuates the shut-off valve 14, and positively cuts off the flow of fuel. In a similar manner this automatic valve is actuated if an excess amount of oil accumulates in the fire pot, in which event said excess oil flows through the discharge pipe 21, into the pan 20, and effects the safety shut-off.

From the feed controlling device 15, and from below the normal level of oil maintained therein, a pipe 22, leads to the burner 8, extending in proximity to the air conduit 4, and entering the latter adjacent an extension 23, of the fire pot, with the delivery end of said pipe just enough below the normal level of oil in the chamber 16, to effect by gravity a desired flow of fuel to the burner. Adjustment to effect this slight difference in level is easily accomplished by raising or lowering the bracket which carries the blower and motor.

The gravity feed of oil through pipe 22, furnishes fuel in the burner and fire pot for combustion which is supported by air from the blower forced through conduit 4. Means are desirable for starting and stopping this flow of fuel through pipe 22, in accordance with the operation of the blower, I therefore provide a valve as 24, operable by the blower

in a manner that will presently appear, to open and effect the flow of fuel and operable when the blower stops to cut off or reduce the flow of fuel. This valve is introduced between the oil level regulating device 15, and the delivery end of pipe 22, in a portion of said pipe sufficiently lowered to provide for a comparatively long valve stem 25, and guide sleeve 25', therefor, which extend well above the level of oil maintained by the float 17. Means for actuating the valve include a thin light disk 26, secured to the valve stem 25, between adjusting nuts 27 and 28. In operable relation to disk 26, is the eccentrically formed end of a rod 29, which rod is extended through the upper portion of conduit 4 and journaled in bearings 30 and 31, provided on the conduit. Within the conduit the rod has rigidly secured thereto a vane 32, normally, by virtue of gravity assuming a vertical position but operable by air pressure created by the blower to swing upwardly and turn the rod so that its eccentric end 33, acting as a cam is effective to engage disk 26, and thereby to open valve 24. When the vane 32, is in its vertical position or that assumed when the blower is stopped the cam 33 passes out of contact with the disk on the valve stem and permits the valve to partly or entirely close as may be desired. It will be observed that the simple construction of the valve permits the stem portion to rotate within the sleeve and the valve to freely seat itself to effectively stop the oil flow, inasmuch as the disk 26 is circular and at all times in position to be engaged by cam 33, without cramping action of the engaging parts. Furthermore it will be clear that the only outside joint between the valve stem and its guiding sleeve is well above the level of oil maintained by the float 17, so that annoying leakage is prevented without recourse to the use of packing, that is to say the valve is a floating one. Normally it tends to close under the effect of its own weight alone and although it freely rotates about its vertical axis it maintains a substantially constant relation operably to its actuating element.

Operation of the apparatus as thus far described includes the use of a pilot flame of gas such as may readily be supplied from the systems quite universally available in urban localities. When such a gas supply is not at hand the necessary pilot flame may be maintained in my apparatus by a small amount of fuel delivered through valve 24. The required opening for this limited amount of flow may be assured by providing for a stop adjustment affecting valve 24 in a manner to prevent complete closure thereof when the valve tends to assume its closed position as when the action of the blower ceases. To serve as adjustable stop means for valve 24, a nut may be threaded on the valve stem adjacent the guide sleeve 25', or a nut (not

shown) may be engaged with the threads on the end of the guide sleeve, (see Fig. 4).

While I have described the specific forms of mechanism illustrated in the drawings, it is distinctly to be understood that many changes may be made therein and in the construction and relative arrangement of parts without departing from the spirit of the invention as defined by the appended claims.

Having thus described my invention, what I claim is:

1. Apparatus of the class described including in combination with a gravity feed pipe line leading to a burner from a device for maintaining a constant level of fuel supply, a valve chamber in the pipe line below the predetermined fuel level, a valve seat in said chamber, a sleeve extending from the valve chamber to a point well above the predetermined fuel level, a valve having a stem freely movable in the sleeve and extended thereabove, means including a cam for lifting the valve, and a disk secured to the valve stem for engagement by the cam, the form of said disk being symmetrical so that the valve may rotate about its vertical axis without changing its balance.

2. Apparatus of the class described including in combination with an air conduit leading from a blower to a burner and a gravity feed pipe line also leading to the burner from a device for maintaining a constant level of fuel supply, a valve chamber in the pipe line below the predetermined fuel level, a valve seat in the chamber, a sleeve extending from the valve chamber to a point well above the predetermined fuel level, a floating valve having a stem extended beyond the end of the sleeve, a disk adjustably secured to the valve stem above the sleeve, a cam positioned below the disk, a rod extended from the cam transversely through the air conduit and a vane secured to the rod within the conduit.

3. Apparatus of the class described including in combination an air conduit and a fuel pipe line, a freely rotatable floating valve in the pipe line having an elongated stem, a symmetrical disk secured to the valve stem, a cam positioned below the disk, and means comprising a vane in the air conduit for oscillating the cam to effect operation of the valve.

4. Apparatus of the class described including in combination an air conduit leading from a blower to a burner and a gravity feed pipe line also leading to the burner, a device in the pipe line and supported by the air conduit for maintaining a constant level of fuel supply, a valve chamber included in the pipe line between the constant level maintaining device and the burner and positioned below the predetermined fuel level, a valve seat in said chamber, a freely rotatable floating gravity closable valve for engaging said

seat and means including an air pressure operated vane in the conduit for lifting the valve.

5. Apparatus of the class described including in combination an air conduit, a fuel feed pipe line adjacent the air conduit, a freely rotatable floating valve having an elongated stem extending from the feed pipe, a disk secured to the outer end of the stem, a 10 sleeve surrounding the stem below the disk, a rod journaled transversely of the air conduit and terminating in a cam for engagement with the disk, and a vane secured to the rod within the conduit.
15. 6. Apparatus of the class described including in combination an air conduit, a fuel feed pipe line adjacent the air conduit, a freely rotatable floating valve having an elongated stem extending from the feed pipe, a symmetrical disk supported by the stem and adjustable longitudinally thereof, a sleeve sur-

rounding the stem below the disk, a rod journaled transversely of the air conduit and terminating in a cam for engagement with the disk, and a vane secured to the rod within 25 the conduit.

7. In combination with a gravity feed pipe line leading from a device for maintaining a constant level of liquid, a valve chamber in the pipe line below the predetermined level of liquid, a valve seat in said chamber, a sleeve extended from the valve chamber to a point above the predetermined level of liquid, a valve having a stem extended through the sleeve and movable rotatively 30 and longitudinally within the sleeve, a symmetrical disk secured to the valve stem, and means operable upon the disk to effect longitudinal movement of the valve while permitting rotary movement thereof.

In testimony whereof I affix my signature.
THURE A. QUART.
